Specification of Letters Patent. Patented Nov. 29, 1921.

Application filed March 28, 1917. Serial No. 157,992.

To all whom it may concern:

Be it known that we, HAYWOOD G. DEWEY and FREDERICK H. KNAPP, citizens of the United States, residing at Westminster, in the county of Carroll and State of Maryland, have invented certain new and useful Improvements in Labeling-Machines, of which the following is a specification, reference being had therein to the accompanying drawing.

This invention relates to labeling machines, and more particularly to machines of this character adapted to apply and affix labels to the body or periphery of cans, cartons, or similar packages of the cylindrical type.

The invention has more particular reference to novel and improved pasting mechanism for use in connection with labeling machines of the above character, the mechanism being adapted to more firmly secure the labels particularly at the opposite edges thereof to the package, thereby overcoming a quite common objection incident to the handling of the labeling packages, namely, the breaking or tearing of the labels at the edges, the mechanism also being of a character to avoid the usual wrinkling of the labels at points intermediate the edges thereof.

In the art to which the invention relates, many attempts have heretofore been made to neatly secure the label and with sufficient firmness to maintain the same immovably in place on the package, a common practice being to apply paste to the entire body of the label or to the major portion of the body of the package to which the label is to be applied. In either case a considerable waste of paste is involved. Then again, in view of the fact that the labels are soaked with the paste at the time of application to the package, the consequent expansion and contraction thereof usually results in an uneven wrinkled appearance, detracting to a considerable extent from the otherwise pleasing character of a labeled package. A further objection incident to applying paste to the entire body of the package resides in the fact that the usual conveyer belts arranged above the packages for imparting rolling movement thereto being brought in contact with the pasted portions of the packages will, of necessity have an application of

paste thereon, which when brought in contact with the labels on the packages will tend to smear or otherwise soil the same.

It has also been quite common in the art to apply paste only to what are known as the "pick up" and "lap" ends of the labels, which method while resulting in a considerable saving of paste, is open to the criticism that the major portion of the label being free from binding contact with the package, is quite apt to become torn, especially at the edges thereof, and, assuming that the paste at the "pick up" portion thereof is not thoroughly and accurately applied, the label will readily become loose and separated from the package.

Still further it has been proposed in the labeling of what is known as "slip cover" cans or cartons, to apply, in addition to the "pick up" and "lap" portions of the label a pasted surface of limited width entirely around the carton at the junction of the flange of the cover with the body, whereby when the label is applied the same will adhere to said pasted surface to form a practically airtight joint or seal at this point and also secure the cover to the body of the carton. This method of affixing the label to the carton while possessing certain advantages is open to the objection that the otherwise substantially continuous and smooth surface of the label is interrupted at the point opposite the junction of the cover of the carton and the body, the label being pressed into contact with the flange of the cover and the adjacent body portion of the carton and presenting a circumferential depression or groove at this point tending to detract more or less from the appearance of the outer surface of the label.

Again, because of the pressure necessary to bring the label into binding contact with the pasted portions of the cover and body portion of the carton at the junction of the cover and body, sometimes results in a collapse of the carton, assuming that the same is, as is oftentimes the case, formed of fragile material. Also, it is found that when the strip of paste is applied intermediate the edges of the label, or at the juncture of the flange of the cover of the carton with the body thereof, a circumferential series of wrinkles will oftentimes appear at this point because of the action of moisture and the subsequent

drying operation, the wrinkles extending in opposite directions, or in directions above and below said juncture between the cover and body. Perhaps an even more serious objection incident to this method of applying labels resides in the fact that the opposite edges of the label are entirely free from adhering contact with the carton with the result that in boxing, shipping, or otherwise handling the labeled cartons, the labels will become broken and torn at these edges and otherwise disfigured.

It is the main object of the present invention to overcome to an appreciable extent all of the above and still further objections which have heretofore manifested themselves in the use of labeling means of prior construction as at present in use. In the accomplishment of this object, it is proposed to firmly affix the label to the can at opposite edges of the label with the result that these edges will not become separated or torn in the handling of the labeled packages, while at the same time the label intermediate the edges thereof will be substantially free from paste and therefore devoid of the customary wrinkles throughout the body thereof.

In the preferred embodiments of the invention herein illustrated, it is contemplated to impart rolling movement to the cylindrical package to be labeled, and in the rolling movement thereof to apply adjacent opposite ends thereof a narrow strip of paste extending entirely therearound, the package in the continued rolling movement thereof being adapted to pick up and have applied to the periphery thereof a label, the strips of paste being separated from one another a distance substantially equal to or slightly less than the width of the labels with the result that the labels will be pasted at the extreme edges thereof, and the body of the label intermediate said pasted portions is substantially free from adherence. It is further proposed by the invention to paste the label at points somewhat removed from the junction between the slip cover and cartons, assuming it is desired to label slip cover cartons, with the result that the pasted edges of the label will present a substantially continuous unbroken, unwrinkled and otherwise neat appearance.

In the practice of the invention, it is possible to firmly affix the labels in place at the pasted edges thereof without undue pressure on the carton which might tend to crush or damage the same, and at the same time it is possible to give to labeled cartons having slip covers the appearance of having a continuous unbroken periphery from end to end thereof, though it is to be borne in mind in this connection that the invention is not limited in adaptation to any particular type of cylindrical package or carton but is

equally useful for labeling packages either with or without slip covers.

A further feature of the invention resides in the provision of means for properly guiding the cartons, the said means preferably including a relatively fixed guide for one end thereof, and associated pasting mechanism for applying annular strips of paste to the cartons adjacent the ends thereof to be engaged by the edges of the label, the said pasting means comprising members movable in a direction toward the fixed guide whereby the application of paste will be made at a fixed predetermined point upon the cartons with the result that said pasted areas will at all times register with the edges of the label.

Other and further improvements and novel details in the construction and arrangement of the various parts of the invention will be appreciated from the description to follow, which, for a clear understanding of the same is to be considered in connection with the accompanying drawings which form a part hereof, and wherein are disclosed for the purpose of illustration convenient and satisfactory embodiments of the invention.

For the purpose of convenience in the description and claims the article to be labeled will usually be referred to as a "can" or "cans", it being understood in this connection however that this term is used in a broad sense, including within its scope various different types of cylindrical packages, cartons or the like, in the labeling of which the machine may be found useful.

In the drawings Figure 1 is a front elevation of a labeling machine with one embodiment of our improvements applied thereto;

Fig. 2 is an enlarged side view of the pasting mechanism for the edges of the label, and associated parts, certain parts being shown in section and others broken away;

Fig. 3 is an enlarged front elevation of the same;

Figs. 4 and 5 are detail views of a modified form of pasting mechanism for the edges of the labels.

With more particular reference to the drawings wherein like reference numerals refer to corresponding parts throughout the several views, a suitable framework is provided generally indicated by the reference numeral 1, the same being mounted upon standards or legs 2 having anti-friction bearings or rollers 3 whereby the machine may be transported from place to place. A can delivery chute 4 is provided adjacent the inlet end of the machine, the said chute being adapted to discharge the cans onto a longitudinally extending runway of any convenient construction, from which runway

the labeled cans are adapted to be discharged onto the delivery chute 5 at the rear end of the machine. The runway which preferably includes laterally spaced track sections 7 is bounded on opposite sides by suitable guides for opposite ends of the cans, one of said guides 8 being preferably fixed in position against movement whereas the opposed guide 9 conveniently takes the form of a yieldably supported strip of yieldable sheet metal. Both guides conveniently extend substantially from end to end of the machine. Arranged intermediate the ends of the runway is a suitable label support 10 or receptacle 10 of any approved type, the receptacle having a movable platform or follower as is obvious adapted to be periodically elevated whereby to properly position the uppermost label to be picked up by a can as it moves along the runway. Also associated with said label receptacle is suitable pasting mechanism generally indicated by the reference character 11, for the purpose of applying to the lap end of the label a strip of paste preferably extending from edge to edge of the label. Arranged at the rear of the label receptacle is a suitable presser or ironing pad 12 upon and over which the labeled cans are adapted to pass. Supported to one side of the framework 1 in any desired manner and in advance of the label receptacle or support 10 is a suitable paste receptacle 13, said receptacle conveniently being detachably secured as by threaded hand bolts 14 to oppositely disposed supporting brackets 15 projecting transversely of the framework 1 and resting upon the upper surface of the side bars of the latter. The brackets have upward extensions 16 and 17 respectively arranged in substantial alinement with the runway track sections 7, the upper edge of the supporting brackets intermediate said extensions 16 and 17 being cut away at 18, and the said track sections 7 having cut out parts for the reception of said extensions 16 and 17. Mounted in suitable bearings in the side walls of the paste receptacle 13 for rotatable movement is a shaft 19 having mounted thereon a paste pick up roll 20 adapted to elevate paste from the receptacle and apply the same to a suitable paste carrying member conveniently taking the form of an endless belt 21 mounted upon a suitable roller 22 which latter is mounted upon a shaft 23 having bearings in the arms of the supporting brackets 15. The shaft 23 for the drive roll 22 of the paste carrying member 21 has connected therewith a suitable gear wheel 24 adapted to mesh with a gear wheel 25 mounted upon the shaft 19 of the paste roll 20 with the result that any movement imparted to the drive roll 22 will impart a reverse rotatable movement to the paste roll 20. The drive roll 22 is adapted to be driven

in any suitable manner but preferably through the medium of means to be now described. 26 is a horizontally disposed rotatable shaft mounted in suitable bearings 27, the said shaft having a gear wheel 28 adapted to mesh with the gear wheel 24. Said shaft 26 also has connected therewith a bevel gear 29 adapted to mesh with a similar gear 30 fixed upon a vertically extending shaft 31 having adjacent the upper end thereof a bevel gear 32 adapted to mesh with a similar gear 33 fixed for rotatable movement with the shaft of one of the supporting rolls for the feed belts 34 to be more particularly referred to hereinafter. It will be observed that as the belt roller is moved such movement is imparted to the vertical shaft 31 and from this shaft to the horizontal shaft 26 thereby rotating the gears 28, 24 and 25. In this way the paste pick up roll 20 and paste applying belt 21 will have simultaneous movement imparted thereto according to the movement of the cans along the runway under the action of the feed belt or belts 34. When the movement of the feed belt is interrupted, the movement of the paste applying belt 21 will likewise be interrupted, and in this connection the shaft 26 may be formed in sections arranged end to end and adapted to be coupled and uncoupled at 95 will through the medium of a suitable clutch sleeve 26^a mounted for sliding movement. In one position of the sleeve 26^a illustrated in Fig. 3 of the drawing the sections of the shaft 26 will be coupled together for rotation whereas when the sleeve is in the opposite position that section of the shaft having mounted thereon the gear wheel 28 will remain stationary during the rotation of the other section of said shaft. Then again 100 when the clutch sleeve is in the last named position the paste receptacle as well as the supporting frame 15 may be removed from the side of the machine. It is desirable to support the upper stretch 110 of the paste belt 21 in position whereby to apply paste to the periphery of the can adjacent the ends thereof, and to this end suitable roller supports 35 and 36 are provided upon the upper ends 16 and 17 respectively 115 of the supporting brackets, the upper stretch of the belt being adapted to project over the periphery of said rollers 35 and 36 whereby to position the pasted surface of the belt in substantially horizontal alinement with the 120 upper surface of the track sections of the runway, to the end that the paste belt at these points will constitute in effect a continuation of said track sections. The paste applying belt is preferably of a width to 125 permit the can X to make a complete revolution while in contact with the paste applying belt whereby a continuous circumferential strip of paste will be applied to the can adjacent the ends thereof.

In order to space that portion of the paste applying belt intermediate the points of contact with the can adjacent the ends thereof, I preferably provide roller bearings 37 and 38 respectively, the same being mounted for loose rotatable movement on the bracket support at points spaced slightly inwardly and downwardly from the roller bearings 35 and 36 respectively. The upper stretch 10 of the paste applying belt is adapted to pass beneath the rollers 37 and 38 with the result that the paste applying belt will be spaced from adhering contact with the body portion of the can. Additional guide rollers 15 39, 40 and 41 may be provided on the supporting bracket for the paste applying belt.

The rotation of the paste applying member 21 is preferably in the direction of the arrow illustrated in Fig. 2 so that any tendency of the belt in the application of the paste to move the cans endwise will be in a direction toward the fixed guide 8 with the result that the application of the strips of paste will at all times be at a uniform point.

25 As previously referred to, the means for imparting rolling movement to the cans along the runway preferably takes the form of an endless belt or belts 34. Conveniently as illustrated more particularly in Fig. 2 a plurality of such belts are provided, the same being mounted upon pulleys 42 and 43 fixed upon suitable supporting shafts one of which shafts is adapted to be driven as by hand or suitable power means.

35 The operation of the construction thus far described may be reviewed as follows: The cans to be labeled are introduced at the inlet end of the machine from the feed chute 4 and when brought into engagement with the 40 runway 7 the feed belts 34 will impart rotatable movement to the cans along the runway. It will be observed in this connection that the belt 34 engage the periphery of the cans at points removed inwardly a considerable distance from the ends thereof so as not to be brought into contact with the pasted areas of the cans.

The cans to be labeled in the continued movement along the runway will be brought 50 into contact with the paste applying member 21 with the result that the contacting portions of said member 21 will apply a continuous narrow strip of paste entirely around the can adjacent each end thereof, 55 the can intermediate said pasted area being free from any application of paste. It should be borne in mind in this connection that the contacting portions of the paste applying member are separated from one another a distance substantially equal to the 60 width of the labels to be applied to the cans with the result that in the continued rotation of the cans the pasted portions thereof will engage the label at the extreme edges 65 thereof. The label being picked up by the

can the same will wrap thereabout, and the lap end of the label having received a strip of paste through the medium of the lap end pasting mechanism 11, this end of the label will adhere to the can and the adjacent opposite end of the label.

Assuming it is desired to apply the labels to slip cover cans, as illustrated in the drawings, it will be noted that the circumferential strip of paste will be applied to the can 75 at points adjacent the edges thereof and at points spaced a considerable distance outwardly from the point of junction of the flange of the covers with the body portion of the cans with the result that the applied 80 label will not be broken or wrinkled at said juncture. The continued movement of the cans will bring the same in contact with the ironing or pressing pad 12 and under slight pressure of the feed belts 34 the edges of the 85 label will be firmly affixed to the can, any surplus paste finding an escape beyond the edges of the label with the result that the edges of the label will have a close snug fit on the can and be practically free from 90 wrinkles. The labeled cans thereupon are delivered to the discharge runway 15, and from the latter to any desirable place of deposit.

In the illustrated embodiment of the invention just described the means for pasting the opposite edges of the labels may also constitute the usual "pick up" pasting means for the labels.

In Figs. 4 and 5 we have illustrated a 100 slightly modified form of paste applying mechanism for securing the edges of the label to the cans. In this embodiment of the invention 50 is a paste pot arranged beneath the runway and supported at opposite sides as 105 by brackets 51 upon the framework 1 of the machine. Mounted for rotatable movement adjacent opposite ends of the receptacle are transversely extending paste rolls 52 and 53 respectively, said rolls projecting longitudinally of the runway and one roll preferably arranged in vertical alinement with each of the runway track sections 7. Arranged to engage the paste rolls 52 and 53 are transfer paste rollers 54 and 55 respectively mounted in suitable brackets 56 projecting upwardly from the paste pot 50. The rolls 54-55 project upwardly into a cut out 110 section of the runway 7 whereby to constitute in effect continuations of the runway and 115 whereby to engage the periphery of the can adjacent the opposite ends thereof so as to apply a narrow strip of paste entirely around the cans, at substantially the same points, and in substantially the same way as in the other 120 illustrated embodiment of the invention previously described. Fixed upon the supporting shafts for the paste wheels 52 and 53 for imparting movement thereto are 125 sprocket wheels 52^a and 53^a adapted to re- 130

ceive a drive chain 57 which latter in turn is adapted to be driven in any suitable manner and from any suitable source by a sprocket 58 mounted upon a drive shaft 59.

5 Also fixed for rotatable movement with the supporting shafts for the paste rolls 52 and 53 are gear wheels 60 and 61 respectively adapted to intermesh with gear wheels 62 and 63 fixed for movement with the transfer paste rolls 54 and 55 respectively. It will be observed that the transfer paste wheels are thereby positively driven, and the direction of rotation being indicated by the arrow, any endwise movement of the 10 cans during the pasting operation will be toward the stationary or fixed guide 8. In this way the narrow strip of paste will be applied at a predetermined point about the periphery of the can so as to accurately 15 register with the edges of the label to be subsequently applied thereto in the manner previously described. As in the previously described construction, it will be observed that the paste applying mechanism is of 20 design and construction whereby to leave substantially free from paste that portion of the can and label intermediate the edges of the latter.

What we claim is:

30 1. In a labeling machine, the combination of a runway for cylindrical articles such as cans, means positioned above the runway for rotating the cans along the same, means for applying to the can adjacent opposite edges thereof only, a circumferential strip of paste, a label support, and guiding means for positioning the pasted strips on the can in contact with the edges only of a label on said support, whereby in 35 the continued movement of the can along the runway the label will be pasted at its extreme edges to the periphery of the can, and whereby that portion of the can intermediate the pasted edges will be substantially free from paste.

40 2. In a labeling machine, the combination of a runway for slip cap cans or the like to be labeled, a label receptacle intermediate the ends of the runway, means for applying the label to the can, and associated means for pasting the labels to the can for a limited distance extending from the outer edges of the label inwardly and entirely around the can, the pasted area of the labels 45 terminating at a point short of the point of juncture between the can cap and body.

45 3. In a labeling machine, the combination of a runway for cylindrical receptacles such as cans, said runway comprising opposed bars adapted to engage the cans adjacent opposite ends thereof, means for rotating the cans along the runway, lap end paste applying means, and pasting means arranged intermediate the ends of the runway at cutout parts thereof adapted to en-

gage the cans to apply adjacent the outer edges only thereof a strip of paste extending entirely around the circumference of the can, and guiding means for the can whereby the pasted strips thereof will align 70 with the extreme edges of the label, and a label support arranged in the path of the cans at a point beyond said pasting means.

4. In a labeling machine, the combination of a runway for cans having slip covers, a label support intermediate the ends of the runway, lap end paste applying means, and means for applying a limited circumferential strip of paste between the label and can at the extreme edges of the label, 75 the body portion of the label between said strips and at the joint between the cover and body of the cans being substantially free from paste.

5. In a can labeling machine, the combination of a runway for cans or the like, means for feeding the cans by a rolling action along the runway, a label support intermediate the ends of the runway, and paste applying means arranged in advance 80 of the label support and movable in a direction transversely of the longitudinal axis of the runway of the machine and adapted to simultaneously apply to adjacent opposite ends of the can only a narrow circumferential strip of paste in alignment with opposite edges of the label to be picked up by the can in the rolling movement thereof, whereby the opposite edges of the label will be firmly affixed to the can to prevent separation and tearing at these points.

6. In a labeling machine, the combination of a runway having at one side a fixed guide for the end of cans or the like mounted on the runway for movement, a label support intermediate the ends of the runway, means for moving the cans along the runway and in contact with the topmost labels on the support whereby the latter are wrapped around the cans, and mechanism 105 arranged forwardly of the label support and movable in a direction toward said fixed guide for simultaneously applying narrow strips of paste entirely around the can adjacent opposite ends thereof and in registration with the edges of the label.

7. In a labeling machine, a runway for cans or the like, a support for the labels intermediate the ends of the runway, pasting means having separate can engaging 110 portions to simultaneously engage the cans adjacent opposite ends thereof whereby to apply paste entirely around the same, the can engaging portions of the pasting means being spaced from one another a distance 115 slightly less than the width of the label, whereby in the rolling movement of the cans the label will be applied and affixed to the can at its edges.

8. In a labeling machine, the combination 120

- of a runway for cans to be labeled, a label support in the path of the movement of the cans, rotatable pasting means having common driving means whereby to simultaneously engage the can adjacent opposite ends thereof to apply narrow strips of paste thereto entirely therearound, the can engaging portions of said pasting means being separated from one another a distance slightly less than the width of the labels mounted on said support whereby said label when wrapped about the can will adhere at its edges to the latter.
9. In a labeling machine the combination of a runway for cans to be labeled, a label support in the path of the movement of the can, rotatable pasting means to engage the can adjacent opposite ends thereof to apply narrow strips of paste thereto entirely therearound, the can engaging portions of said pasting means being separated from one another a distance slightly less than the width of the labels mounted on said support whereby said label when wrapped about the can will adhere at its edges to the latter, guide ways for the runway, one of which is yieldable and the other fixed, and the movement of the paste applying means being in a direction having a tendency to move the cans into contact with said fixed guide.
10. In a can labeling machine the combination of means for applying a narrow strip of paste entirely around a slip cover can adjacent one end thereof, and means for applying a label around the can and securing it at one extreme edge to said pasted surface of the can, the pasted area of said edge of the label terminating at a point short of the juncture between the slip cover and body of the can.
11. In a labeling machine for slip cover cartons and the like, the combination of a runway, means for feeding the cartons along the runway, a label support, and means in advance of the label support adapted to apply adjacent opposite ends of the can a circumferential strip of paste whereby in the rolling movement of the cans the labels will be picked up by the cans and pasted to the opposite ends of the cans, and associated means whereby said pasting means will maintain that portion of the can at the junction of the cover and body free from paste and thereby prevent wrinkling at this point.
12. In a labeling machine for cartons having slip covers or caps at the ends thereof, a label receptacle, a runway for the cans in advance of the label receptacle, and means for simultaneously applying a narrow strip of paste to the flanged portions of said covers or caps, adjacent the extreme ends of the cartons, and means whereby the body portion of the carton and the edges of the flanges of the covers or caps are maintained free of paste under the action of said pasting means.
13. In a can labeling machine the combination of an elongated runway for cans and the like, a label receptacle intermediate the ends of the runway adapted to contain a supply of labels to be picked up by the rolling cans, a pasting member extending transversely across the runway, and means for guiding said member whereby the pasted portions thereof only are engaged by the moving cans to apply narrow strips of paste adjacent opposite ends of the cans.
14. In a can labeling machine the combination of a runway for cans, a label support intermediate the ends of the runway, and can pasting means including an endless paste carrier extending transversely of the runway, and guiding means for the paste carrier whereby to position pasted portions thereof to be engaged by the moving can and whereby to separate the remaining portions of the carrier from said can.
15. In a can labeling machine the combination of a runway for cans and the like, of a label receptacle intermediate the ends of the runway, and means to apply to the can adjacent the opposite ends thereof a circumferential strip of paste whereby in the rolling movement of the can the pasted surfaces of same will engage edges of the label to firmly affix the same, the said means comprising an endless carrier projecting transversely across the runway, supports for the carrier, to position spaced portions thereof to contact with the can, and to space that portion of the carrier intermediate the supports out of contact with the body of the can.
16. In a labeling machine, the combination of an elongated runway for cans and the like, a label support intermediate the ends of the runway, paste applying means adjacent the runway and extending lengthwise of the runway a sufficient distance to permit a can to make a complete revolution while in contact with said means, and said paste applying means being constructed and arranged whereby to form a circumferential band of paste around the can adjacent both ends thereof, and means above the runway to engage the cans at a point between said pasted bands whereby to rotate the cans in contact with the labels, and whereby the pasted bands of the can will engage the labels at the extreme edges thereof to prevent separation or tearing of said edges, and means whereby the can at points between said pasted bands will be spaced from contact with said pasting means.
17. In a labeling machine, the combination of a runway for cans or the like, a label

support intermediate the ends of the runway, and means in advance of the label support in the path of the can for applying a circumferential narrow strip of paste to the 5 can, whereby the can in its movement along the runway will contact with the topmost label or label support and cause the label to adhere to the pasted area of the can, said means comprising an endless paste belt 10 extending transversely across the runway and rotatable in a direction transverse to the rolling movement of the can along the runway, and a plurality of supports for the belt, one of which supports contacts the belt 15 with the can, and another of which spaces the major portion of the belt out of contact with the can.

18. In a labeling machine, the combination of a runway for cans or the like, a label support intermediate the ends of the run- 20

way, and pasting mechanism for applying adjacent opposite ends of the can a circumferential narrow strip of paste, said pasting mechanism including an endless paste belt 25 extending transversely across the runway, rollers over which the belt passes whereby to engage the can as it moves along the runway, and means interposed between said rollers and under which the belt passes whereby to space the body portion thereof 30 from the body portion of the can.

In testimony whereof we hereunto affix our signatures in the presence of two witnesses.
